United States Patent Office

Des. 212,141
Patented Aug. 27, 1968

212,141

BATH MAT

Paul C. Mallonn, Wooster, Ohio, assignor to Rubber-maid Incorporated, Wooster, Ohio, a corporation of Ohio

Filed Oct. 30, 1967, Ser. No. 9,203

Term of patent 14 years

(Cl. D92—21)

FIG. 1

FIG. 2

FIG. 3

FIG. 1 is a perspective view of a bath mat embodying my new design.

FIG. 2 is an enlarged fragmentary plan view of a corner thereof.

FIG. 3 is an enlarged fragmentary sectional view on line 3—3 of FIG. 2.

The bottom, as indicated in FIG. 3, is flat and also plain.

I claim:

The ornamental design for a bath mat, as shown and described.
